United States Patent

Des. 237,382
Patented Oct. 28, 1975

237,382

HANDRAIL

Gary F. Bartlett, Muncy, Pa., assignor to Construction
Specialties, Inc., Cranford, N.J.

Filed Dec. 28, 1973, Ser. No. 429,110

Term of patent 14 years

Int. Cl. D25—02

U.S. Cl. D13—7 R

FIG. 1

FIG. 2

FIG. 3

FIG. 1 is a front elevational view of a handrail incorporating my new design, a medial portion thereof being broken out to indicate a member of indeterminate length; FIG. 2 is a rear elevational view thereof; and FIG. 3 is an end view thereof.

I claim:

The ornamental design for a handrail, as shown and described.
